UNITED STATES PATENT OFFICE.

JOHN PATTERSON, OF AURORA, ILLINOIS.

COAT-HOOK.

No. 855,586.

Specification of Letters Patent.

Patented June 4, 1907.

Application filed April 9, 1906. Serial No. 310,702.

To all whom it may concern:

Be it known that I, JOHN PATTERSON, a citizen of the United States, residing at Aurora, in the county of Kane and State of Illinois, have invented certain new and useful Improvements in Coat-Hooks, of which the following is a specification.

My invention relates to coat hooks and especially to that class having locking means 10 to prevent theft of the garment hung thereon.

The device is especially useful for securing outer garments such as overcoats and cloaks and is adapted to be used wherever such garments are temporarily laid aside and is especially applicable for use in public places such as restaurants, reading rooms and 15 places of similar character.

The chief objects of my invention are to provide a simple, efficient and durable locking hook for coats and cloaks.

Another object of the device is to provide an automatic lock for a coat hook, so that the garment placed upon the hook can be instantly locked thereon and protected from 25 theft.

Another object is to provide a separate and special key for each hook thus preventing the possibility of removal of the garment unless that special key is used to unlock the device.

With this and other minor objects in view 30 the invention consists of certain novel features of construction, combination, and arrangement of parts, as will be hereinafter more fully described and particularly pointed 35 out in the appended claims.

In the drawing hereunto annexed and forming a part of this specification:—Figure 1 is a side view, in elevation, of my improved cloak and coat hook adapted to be secured to a 40 wall or casing and showing the method of securing a coat thereon; a portion being broken away to disclose some of the inner parts; Fig. 2 is a side view in elevation, of the same device in an unlocked position, and Fig. 3 is a longitudinal section through the device in its 45 locked position, some portions being broken away to show certain parts more clearly.

Referring to the drawing the numeral 4 indicates a base plate from which projects a 50 cylindrical arm 5, preferably formed integral with said plate and provided with a bulbous head 6. Above the said arm 5 and also formed integral with the plate 4 is a lug 7. A retaining member 8, semi-cylindrical in form 55 and having a concavity on the under side is adapted to engage the upper surface of the

arm 5, and is provided at its outer extremity with a cap 9 adapted to cover the upper and outer surfaces of the head 6. From the upper side of this retaining member projects a lug 10 pivotally secured to the lug 7 by a rivet 11. The interior of the arm 5 is provided with a cylindrical bore 12 throughout the greater part of its length in which is slidably mounted a tubular latch-bolt 13, held in an extended position within the said bore by means of a spring 14, which abuts at one end against a pin 15, which is fixed in the arm 5 and passes through slots 15^a in the said latch bolt 13, the opposite end of the spring engaging 60 an annular abutment 16 formed integral with the said bolt. At the rear end of said latch bolt 13 is a notch 17, and at the front end a projecting beveled latch head 18. In the upper wall of the arm 5 is a slot 19 which 65 communicates with the interior bore 12 and permits the entrance of the free end of a lug 20 fixed in the retaining member 8 and provided with a slot 21. The latch head 18 engages this slot and prevents movement of the 70 retaining member when said parts are in engagement. The under surface of the anterior portion of the member 8 as well as its cap 9 is formed with a recess 22, thus leaving a moderate interval between the adjacent surfaces 75 of the retaining member and the arm 5.

In order to retract the latch bolt 13 and thus release the lug 20 by the removal of the latch-head 18 from engagement with the slot 21, I provide a lock 23 of any common form, 80 preferably attached to the rear face of the base plate 4. The end of the locking bolt 24 is beveled and so related to the notch 17 that when the said lock bolt 24 is projected upward by means of a key 25 the said bolt 24 85 will penetrate the notch 17 and its beveled face engaging the lug 26 will retract the latch bolt 18, thus removing the latch-head 23 from the lug 20, in which case the retaining member will be free to be raised to the position shown in Fig. 2, thereby releasing the garment previously held upon the arm 5 by said retaining member.

The method of operating the device is as follows:—The retaining member 8 is raised to 105 the position shown in Fig. 2, where it is held by gravity against the wall or casing to which it may be attached and the lock-bolt 24 is retracted within the casing of the lock 23, the latch bolt 13, then taking the position 110 shown in Fig. 3. The coat or other garment is now hung upon the projecting arm 5 so as

to completely cover the head 6, and the retaining member 8 is lowered thereon until the latch head 18 engages the lug 20, which it will do automatically since the mutual relation of the parts is such that the lower end of the lug 20 will strike the beveled face of the latch head 18 and thus retract the latch bolt 13 until the said lug is depressed sufficiently to permit the latch head 18 to enter the slot 21 under the impulse of the spring 14. The user can then take the key, which may have been left in the lock or hung upon an adjacent nail or peg, and place it in his pocket until he desires to use the garment. He then raises the lock bolt 24 by means of the key, which he leaves in the lock, and raising the retaining member 8, the garment can be removed from the arm. It will be noted that turning the key 25 to lock the bolt 24 unlocks the latch bolt 13; and, conversely, when the garment is locked on the arm 5 the bolt 24 is in an unlocked position.

Having thus described my invention what I claim, is:—

25 1. A device of the character described including a base plate, an arm projecting from said plate and having a knob on its outer end, a retaining member adapted to removably engage and overlap the said arm and knob, 30 means for locking said retaining member in apposition with the said arm, and separate key-operated means for releasing said member from its locked position.

35 2. A device of the character described including a base plate having a tubular projecting arm formed integral therewith, a latch-bolt adapted to be reciprocated within said tubular arm, a spring to extend said latch bolt, a retaining member provided with

a lug adapted to automatically engage said latch-bolt, and separate key-operated means for retracting said latch bolt to release said retaining member, said means secured to the rear side of said base-plate.

3. A device for the purpose specified including a base-plate, a tubular arm projecting from said base plate and provided with an enlarged head, a latch-bolt adapted to be reciprocated within the tubular arm, a retaining member co-extensive with the said arm and adapted to engage its upper portion and overlap the said enlarged head, a lug secured to said retaining member, a latch-head attached to said latch-bolt and adapted to engage said lug, means for yieldingly retaining said latch-bolt and head in engagement with the said lug, separate key-operated means for releasing the said latch-bolt and head from engagement with the said lug, and means for raising the said retaining member 60 from the said arm when so released.

4. In a coat-hook, a base-plate, a tubular arm extending from said plate, a hollow latch-member slidably mounted in said arm, a spring arranged in said latch and adapted to extend the same, a retaining member pivoted on said base plate and adapted to partly embrace said arm, a lug on said member adapted to engage said latch, and a lock secured to the rear of said base plate, said lock comprising a bolt adapted to engage and hold said latch against the action of said spring.

In testimony whereof I affix my signature in presence of two witnesses.

JOHN PATTERSON.
